(57) CLAIM

The ornamental design for a vehicle headlight, as shown and described.

DESCRIPTION

FIG. 1 is a perspective view of a vehicle headlight;

FIG. 2 is a front view thereof;

FIG. 3 is a left side view thereof;

FIG. 4 is a top view thereof;

FIG. 5 is an enlarged view of FIG. 3 thereof;

FIG. 6 is a first enlarged perspective view thereof;

FIG. 7 is a second enlarged perspective view thereof;

FIG. 8 is a third enlarged perspective view thereof; and,

FIG. 9 is a fourth enlarged perspective view thereof.

The broken lines depict portions of the vehicle headlight in which the design is embodied that are not considered part of the claimed design.

The dashed lines show a boundary between the claimed design and unclaimed portions.
